J. LEDWINKA.
VEHICLE TOP IRON SUPPORT.
APPLICATION FILED MAR. 21, 1916.

1,214,932.

Patented Feb. 6, 1917.

By his attorney
Inventor
Joseph Sedivinka
Samuel F. Darby

UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

VEHICLE-TOP-IRON SUPPORT.

1,214,932.

Specification of Letters Patent.

Patented Feb. 6, 1917.

Application filed March 21, 1916. Serial No. 85,599.

To all whom it may concern:

Be it known that I, JOSEPH LEDWINKA, a citizen of the United States, residing at Philadelphia, county of Philadelphia, State of Pennsylvania, have made a certain new and useful Invention in Vehicle-Top-Iron Supports, of which the following is a specification.

This invention relates to top iron supports for vehicles.

The object of the invention is to provide a top iron support which is simple in construction, strong, durable and efficient and which does not interfere with the easy application of upholstery or trim to the vehicle.

Other objects of the invention will appear more fully hereinafter.

The invention consists substantially in the construction, combination, location and relative arrangement of parts all as will be more fully hereinafter set forth, as shown in the accompanying drawing and finally pointed out in the appended claims.

25 Referring to the drawing:

Figure 1 is a view in vertical section on the line 1, 1, Fig. 2, through the side wall of an automobile body showing the application thereto of a top iron support in accordance with my invention.

Fig. 2 is a section on the line 2, 2, Fig. 1, looking in the direction of the arrows.

Fig. 3 is a broken view in perspective showing another form of application of a top iron support embodying the principles of my invention.

Fig. 4 is a view in section on the line 4, 4, Fig. 3, looking in the direction of the arrows.

40 The same part is designated by the same reference signs wherever it occurs throughout the several views.

In the application of top supporting irons to automobile and other vehicle bodies, as 45 usually carried out in practice, the top irons form part of or are carried by struts or angle pieces, rods or the like, secured inside the vehicle body and extending up above and thence outwardly beyond the upper edge 50 of such body. In such constructions it is necessary to cut and fit the upholstery or trim usually applied to the inside vertical surfaces of the vehicle body at the points

where the top supporting irons extend over and beyond the upper edge of the body, in 55 order to secure a neat, slighty and finished application of the upholstery or trim at and around such irons or their supports. This is objectionable because of the cutting and fitting of the trim or upholstery, thereby 60 rendered necessary, and also because of the time, skill and labor required to effect such cutting and fitting, which adds cost to the production of the complete body. Where vehicle bodies equipped with top supporting 65 irons are turned out in large quantities and at small margin of profit, this additional cost becomes substantial in amount.

It is among the special purposes of my invention to provide a structure of top iron 70 support which avoids the objections noted, as well as other objections, and which also secures strength and rigidity which characteristics are desirable in structures of this 75 nature.

In carrying out my invention I propose to employ a channel which is applied to the inner vertical wall of the body, and to house a supporting block within said channel, and to extend the end of the top iron from outside through the wall of the vehicle body, the said block and channel and clamp the same therein, thereby avoiding the necessity of extending the top iron above and over the top edge of the body where it would interfere with the easy and ready application of the trim or upholstery, while at the same time securing strength and rigidity in the support for such top iron.

I have shown various ways of carrying 80 out the principles of my invention and it is obvious that the same may be applied in practice in still other specific ways without departure from the spirit and scope of my invention as defined in the claims.

Referring to Figs. 1 and 2, the vertical wall of the vehicle body shell is shown at 5, and this may be of any suitable material, form or construction. Applied and secured to the inner surface of the body shell is a 100 channel member 6, which, in this instance, extends from the top edge of the body shell to the floor of the vehicle. Housed within the channel of member 6 is a block 7, and registering holes are formed through the 105 body shell 5, the block 7, and the channel

member 6. The top supporting iron 8 is shown in this instance in the form of a gooseneck member with a shoulder 9 formed thereon or carried thereby adjacent one end 5 thereof. The end of said iron which extends beyond the shoulder is passed through the registering holes in the shell, block and channel and a nut 10 applied thereto serves to securely clamp the shoulder 9 up against 10 the outer surface of the body shell and hold the top iron rigidly and firmly in place. The channel member 6 serves not only as a housing for the block 7, but also to strengthen the body shell and aids in furnishing a strong rigid support for the top iron and for the weight of the top when applied thereon.

In Figs. 3 and 4, I have shown a slightly modified arrangement wherein, instead of 20 the channel member 12, extending the entire vertical height of the body shell 5, it is made shorter and is secured at its lower end to a strap iron 11 which is applied to the inside surface of the body shell. This strap iron is 25 employed in some types of automobile bodies to afford means for securing the mud guard to such body. In such case I employ this strap iron also to secure the channel members thereto. In other respects the structure 30 including the shouldered gooseneck or iron 8, channel member 12, the block 7, and the clamp nut 10, remain the same as corresponding parts above described.

While I have described my invention as 35 applied to a top iron support it will be evident that the same principles of construction may be equally well applied to supporting irons or members employed in connection with automobile or other vehicle bodies for 40 other purposes besides top supports.

Having now set forth the objects and nature of my invention and constructions embodying the principles thereof, what I claim as new and useful, and of my own invention, and desire to secure by Letters Patent is:—

1. In a top iron support for vehicles, and

in combination with the vehicle body shell, a channel member applied to the inner surface of the body shell, a block housed within the 50 channel of said member, said shell, block and channel member having registering holes therethrough, and a supporting iron having its end inserted through said holes and a nut applied thereto to clamp the parts 55 together.

2. In a top iron support for vehicles, and in combination with the vehicle body shell, a channel member applied to the inner surface of the body shell, a block housed within 60 the channel of said member, a shouldered supporting iron having its end extended through said shell block and channel member, and nut to clamp said parts together.

3. In a top iron support for vehicles, and 65 in combination with the vehicle body shell, having a strap iron applied to the inner surface of said shell, a vertically extending channel also applied to the inner surface of the shell and secured thereto and to the 70 strap iron, a supporting iron having a shouldered end extended through the shell from the outside and through said vertically extending channel, and a nut applied to said iron end to clamp the parts together. 75

4. In a top iron support for vehicles, and in combination with the vehicle body shell, a strap applied to the inner surface of said shell, a supporting member also applied to the inner surface of said shell and secured to 80 said strap, a supporting iron having a shouldered end extended through the shell from the outside, and through said supporting member, and a nut applied to said iron end to clamp the parts together. 85

In testimony whereof I have hereunto set my hand in the presence of the subscribing witnesses, on this 6th day of March A. D., 1916.

JOSEPH LEDWINKA.
